UNITED STATES PATENT OFFICE.

IRIA W. FOLTZ, OF CHICAGO, ILLINOIS.

ANNEALING-FURNACE.

1,258,885.

Specification of Letters Patent. Patented Mar. 12, 1918.

Application filed March 23, 1916. Serial No. 86,094.

To all whom it may concern:

Be it known that I, IRIA W. FOLTZ, a citizen of the United States of America, and a resident of Chicago, county of Cook, and 5 State of Illinois, have invented certain new and useful Improvements in Annealing-Furnaces, of which the following is a specification.

This invention relates to annealing furnaces, designed for the burning of coal or other solid fuel, and has for its objects to provide improved means whereby the desired temperatures may be uniformly maintained throughout the furnace and the cost 10 of operation thereof reduced; to provide means for completely consuming all gases distilled from the fuel body, which gases, if not fully consumed, have a harmful action on the metal being annealed in the furnace; 15 to provide annealing furnaces with improved means for pre-heating the air supplied to the various compartments of the furnace; to provide improved means for obtaining an even supply and uniform distribution of the pre-heated air throughout the furnace; and to provide improved 20 means for collecting the gases distilled in the fuel burning region of the furnace, mixing heated air therewith and properly delivering the mixture to the combustion or 25 annealing chamber of the furnace to insure its complete combustion.

An illustrative embodiment of this invention is shown in the accompanying drawings, 30 in which—

Figure 1 is a vertical longitudinal section of the furnace taken on the line A—A of Fig. 2.

Fig. 2 is a transverse sectional elevation 40 on the line B—B of Fig. 1.

Fig. 3 is a perspective view of a portion of an air supply conduit.

Fig. 4 is a perspective view of a portion of an air distributing conduit.

Fig. 5 is an enlarged sectional plan view 45 taken on the line C—C of Fig. 2.

Many annealing furnaces in which the annealing chambers thereof are heated by burning a solid fuel in a fire-box located 50 in the furnace are more or less unsatisfactory because the heat is not evenly distributed and maintained throughout the annealing chamber and also because unconsumed gases are permitted to pass through the annealing chamber, to the injury of the cast-

ings therein, unless the same are inclosed in air-tight containers.

Accordingly, one of the purposes of the present design is to provide an annealing furnace in which the combustion is practically uniform throughout the combustion chamber and in which the temperature thereof may be so controlled that the same will not vary more than a few degrees from some predetermined temperature during a considerable period of time and also to provide means for insuring the complete combustion of all gases which may harm the material being treated in the furnace.

In the construction shown in the drawings, the annealing furnace is formed by the walls 1, 2, and 3, a roof 4, and floor 5, all of the usual reinforced brick construction. The front end of the furnace is closed by the temporary brick wall 30 which, as 70 usual, is made removable to permit access to the annealing chamber 17. Adjacent to the wall 1 and preferably at one corner of the furnace, is provided a fire-box 6 having a grate 7 which spans an opening 8 in the 75 floor of the furnace. The ash-pit 9 is provided with the usual door, having means for regulating or preventing a draft there-through. The firing door 11 closes the usual opening 10 passing through the rear 80 wall of the furnace.

The fire-box is formed by walls 1 and 2 in connection with the side wall 12, a horizontally disposed top wall 13, and a bridge 16. The top wall 13 is provided with air 85 conduits 13.1, as shown in Fig. 5. These conduits communicate at their rear ends with air inlets or short conduits 13.2 in the top wall 13, and are provided with outlets 13.3 at the front end of the fire-box. The 90 purpose of these conduits is to supply heated air to gases arising from the fuel body on grate 7. Such gases and the heated air mixed therewith, then pass through apertures 15.1 into vertically extending conduits 100 15 in a baffle wall depending from the roof 13 of the fire-box. The gases and air mixed therewith are discharged from the lower end of baffle wall 14, at which point they are ignited and pass upwardly between the wall 105 14 and bridge 16 around the upper edge of the bridge into the combustion or annealing chamber 17.

The sides of the fire-box are provided with false walls 18 spaced slightly apart 110

from the walls 2 and 12, said false walls being provided with apertures 19 through which air may be admitted to facilitate combustion. A short duct 20 located on the floor at one end of the grate 7 provides communication between the spaces adjacent to the walls 2 and 12. It may be seen in Fig. 2 that the lower ends of vertical conduits 13.2 communicate with said spaces and receive air therefrom.

Pre-heated air is supplied to the different compartments of the furnace by air inlet conduits 21 which extend to the rear end of the furnace and communicate with short vertical ducts 21.1. The ducts 21.1 communicate with supply ducts 23 which carry preheated air to a series of distributing conduits 22, the flow of air being as indicated by the arrows in Fig. 1. Preheated air is supplied to the space back of the false walls 18 by a vertical duct 21.2 which communicates at its upper end with one of the ducts 23 and at its lower end with the duct 20, and with duct 21.3, which communicates with said space. The inlet conduits 21 are horizontally disposed along the side walls 2 and 3 of the annealing or secondary combustion chamber and the air passing therethrough is heated by the combustion of gases in this chamber. The outer ends of conduits 21 may be provided with dampers in the form of doors 25 for controlling the supply of air to the furnace chambers. One of these doors is shown open in Fig. 1.

The distributing conduits are arranged at intervals along the top of the chamber 17 and are provided with outlet apertures 24 in their lower faces. Air is supplied in uniform quantities to the distributing conduits by graduating the supply pipes 23 in proportion to the number of distributing conduits supplied.

The products of combustion may escape from the annealing chamber by providing outlets 26 in the side walls of the chamber which communicate with a space 27 beneath the floor 5. The gases pass from this space to a chimney by means not shown.

In the operation of the device, the air is drawn in through the inlet conduits 21 and heated as it passes therethrough by the combustion of gases in the annealing chamber 17. This heated air is supplied to the firebox by passing through the apertures in the false walls thereof. Such heated air is also supplied to the annealing or secondary combustion chambers by the distributing conduits 22 which communicate with the inlet conduits by means of the graduated supply conduits 23. Gas distilled from the fuel and rising into the more or less confined space above the grate is mixed with air which enters the vertical conduits 13.2 from the

space between the side walls of the fire-box and the false walls 18. This air is superheated while passing through the conduits 13.1 in the roof of the fire-box. Such air and gasses mixed therewith enter the inlets 15.1 in baffle wall 14 and then pass downwardly, leaving the baffle wall at a point 70 where flames from the burning fuel sweep around the same, thus insuring good ignition of the mixture. The fuel is thrown to the rear of the fire-box until it is at a higher level than the lower end of the baffle wall 75 14, thus causing the unconsumed gases issuing from the top of the fuel pile to enter the inlets 15.1. The conduits 22 supply additional heated air at different points in the combustion chamber for the purpose of 80 bringing about the combustion of the remaining unconsumed gases.

Although but one specific embodiment of this invention has been herein shown and described, it will be understood that numerous details of the construction shown may be altered or omitted without departing from the spirit of this invention as defined by the following claims.

I claim:

1. A furnace of the class described, comprising a wall structure forming a fire-box and an annealing chamber, apertured false walls spaced inwardly from the side walls of said fire-box, an air heating conduit located at the sides of said annealing chamber and having exposed surfaces therein, said conduits communicating with the space between the side walls and false walls of said fire-box and also having a plurality of 100 outlets in said annealing chamber.

2. An annealing furnace, comprising a fire-box, a combustion and annealing chamber, air inlet conduits arranged along the sides of said combustion chamber so as to 105 be heated by the combustion of gases in said chamber, air supply conduits arranged at opposite sides of said combustion chamber, distributing conduits located at intervals along the top of said combustion chamber 110 transversely to and providing communication between said supply conduits.

3. A furnace, comprising a wall structure formed to provide a fire-box and a combustion chamber, a roof for the fire-box, 115 said roof being provided with an air conduit having an outlet in said fire-box, and a baffle wall depending from said roof of the fire-box having a vertically extending passage therein communicating at its upper end with the fire-box and at its lower end with the combustion chamber.

Signed at Chicago this 16th day of March 1916.

IRA W. FOLTZ.
